UNITED STATES PATENT OFFICE.

CARLO TOMMASI, OF BASEL, SWITZERLAND, ASSIGNOR TO ELEKTRIZITATSWERK LONZA, OF GAMPEL, CANTON OF VALAIS, SWITZERLAND, A CORPORATION OF SWITZERLAND.

BURNER FOR METALDEHYDE.

Application filed July 19, 1921. Serial No. 485,923.

To all whom it may concern:

Be it known that I, CARLO TOMMASI, a subject of the King of Italy, and resident of Basel, Switzerland, have invented a new and useful Burner for Metaldehyde, of which the following is a full, clear, and exact specification.

A drawback of all known burners for metaldehyde consists in the fact that after 10 a long burning the burner becomes so hot that when the flame is extinguished a troublesome emission of vapors of acetaldehyde resulting from the depolymerization of the metaldehyde takes place and thus causes 15 losses of fuel. These inconveniences are avoided by the burner of the present invention wherein the walls of the burner, surrounding the metaldehyde, that is to say subjected to heating by the flame, are provided with a means for cooling them by a liquid. 20 Generally it is sufficient to cool the support of the body of solid fuel.

In Figs. 1 and 2 of the annexed drawing there are shown in vertical section two examples of burners carried out according to 25 the invention.

In the example of Fig. 1 A designates the support of the body B of solid fuel, which is supposed to be a pastil of metaldehyde. 30 The support A is hollow and is filled with a cooling liquid as for instance water, glycerin, an aqueous solution, etc. In order to take into consideration the expansion of the liquid under the influence of the heat, the 35 vessel formed by the support A can be provided at its top with an orifice *a* or it is not entirely filled up with liquid, leaving thus an air cushion C in the upper part of the support.

40 Fig. 2 shows a burner with a protecting sheath receiving the body of metaldehyde B. This protecting sheath *b* forms a part of vessel A filled with water provided with an orifice *a* and enclosing an air cushion C. 45 The metaldehyde body B is pushed automatically upward by a spring D against a wire E fixed on the top of the vessel A and limitating the protrusion of the metaldehyde body B from its protecting sheath *b*.

50 I am aware that the cooling of a candle sliding-tube by a water container in order to keep the candle cool and to avoid wasting of the said candle is already known and

that it has also been proposed heretofore to place a candle in a water bath keeping the 55 candle floating and causing it to rise automatically as it burns off, in order to keep the candle practically at a constant level.

But previously to the present invention nobody had proposed a burner for metaldehyde in which the burner walls surrounding 60 the metaldehyde were provided with a means for cooling them by a liquid in order to prevent the depolymerization of the metaldehyde after the extinction of the flame. 65

What I claim is:

1. A burner for metaldehyde wherein the walls of the burner surrounding the metaldehyde are provided with a means for cooling them by a liquid, in order to prevent 70 the depolymerization of the metaldehyde.

2. A burner for metaldehyde comprising a hollow support for a metaldehyde body of the said support containing a liquid, in order to prevent the depolymerization of the 75 metaldehyde.

3. A burner for metaldehyde comprising a hollow support for a metaldehyde body, the said support containing a liquid in order to prevent the depolymerization of the met- 80 aldehyde and being provided at its top with an orifice.

4. A burner for metaldehyde comprising a protecting sheath for a body of metaldehyde, the said sheath being a part of a vessel 85 surrounding it and containing a liquid, and a spring pushing the said body upwards against a wire fixed on the upper part of the said vessel and limitating the protrusion of the said body from the said sheath. 90

5. A burner for solid fuel comprising a protecting sheath for a body of metaldehyde, the said sheath being a part of a vessel surrounding it and containing a liquid and provided with an orifice at its top, and a spring 95 pushing the said body upwards against a wire fixed on the upper part of the said vessel and limitating the protrusion of the said body from the said sheath.

In witness whereof I have hereunto 100 signed my name this 27th day of June, 1921, in the presence of two subscribing witnesses.

CARLO TOMMASI.
